(57) **ABSTRACT**

A switch includes a movable portion, a first electrode and a second electrode. The movable portion is provided on a substrate and moves with respect to the substrate. The first electrode is provided on the movable portion. The second electrode is able to contact with the first electrode and is fixed to the substrate. $f \times R_o \times C \leq 1.6 \times 10^{-4}$ when an operation frequency is represented as “f” (Hz), a transmission impedance is represented as “Ro” (Ω), and a capacitance in “OFF” state between the first electrode and the second electrode is represented as “C” (F).

SWITCH WITH MOVABLE PORTION

BACKGROUND OF THE INVENTION

1. Field of the Invention

This invention generally relates to a switch, and in particular, relates to a micro machine switch having a movable portion.

2. Description of the Related Art

A switch for switching a high-frequency signal has been used widely. For example, a GaAs semiconductor switch is used in a switching circuit for switching between sending and receiving circuits such as a cellular phone, because the GaAs semiconductor switch has high responsivity. However, with respect to the GaAs substrate switch, an electrical loss in "ON" state is large and isolation in "OFF" state is low. And so, a MEMS (Micro Electro Mechanical System) switch manufactured with a micro machine processing technology using a Si substrate is noted. In the MEMS switch (Micro Machine Switch), the electrical loss in "ON" state is small and the isolation in "OFF" state is large, because an electrical contact is turned on and off directly. Japanese Patent Application Publication No. 2005-243576 discloses the MEMS switch.

However, the isolation of the MEMS switch in the "OFF" state is degraded when the operation frequency is high. For example, there is a demand for reducing the isolation level in the "OFF" state less than -30 dB. However, there is a case where the isolation level in "OFF" state is more than -30 dB in the MEMS switch using a high frequency wave. A requirement affecting the isolation level in "OFF" state has not been examined with respect to the MEMS switch.

SUMMARY OF THE INVENTION

The present invention provides a switch that may enlarge the isolation in "OFF" state thereof.

According to an aspect of the present invention, preferably, there is provided a switch including a movable portion, a first electrode and a second electrode. The movable portion is provided on a substrate and moves with respect to the substrate. The first electrode is provided on the movable portion. The second electrode is able to contact with the first electrode and is fixed to the substrate. $f \times R_{ox} C \leq 1.6 \times 10^{-4}$ when an operation frequency is represented as "f" (Hz), a transmission impedance is represented as "Ro" (Ω), and a capacitance in "OFF" state between the first electrode and the second electrode is represented as "C" (F). With the above-mentioned configuration, the isolation may be high in "OFF" state.

According to another aspect of the present invention, preferably, there is provided a switch including a movable portion, a first electrode, a second electrode, and a third electrode. The movable portion is provided on a substrate. The first electrode is provided on the movable portion. The second electrode and a third electrode are able to contact with the first electrode and are fixed to the substrate. A high frequency signal flows from one of the second electrode and the third electrode to the other through the first electrode. $f \times R_{ox} C \leq 3.2 \times 10^{-4}$ when an operation frequency is represented as "f" (Hz), a transmission impedance is represented as "Ro" (Ω), and a capacitance in "OFF" state between the first electrode and the second electrode and between the first electrode and the third electrode is represented as "C" (F). With the above-mentioned configuration, the isolation may be high in

2

the switch that turns on and turns off a flow of electrical power from the second electrode to the third electrode.

BRIEF DESCRIPTION OF THE DRAWINGS

5 Preferred embodiments of the present invention will be described in detail with reference to the following drawings, wherein:

10 FIG. 1A illustrates a top view of a switch in accordance with a first embodiment;

FIG. 1B illustrates a cross sectional view taken along a line A-A of FIG. 1A;

FIG. 2A illustrates "OFF" state of a switch in accordance with a first embodiment;

15 FIG. 2B illustrates "ON" state of a switch in accordance with a first embodiment;

FIG. 3 illustrates an equivalent circuit of a switch in accordance with a first embodiment;

20 FIG. 4A illustrates a top view of a switch in accordance with a second embodiment;

FIG. 4B illustrates a cross sectional view taken along lines A-A and B-B of FIG. 4A;

FIG. 4C illustrates a cross sectional view taken along a line C-C of FIG. 4A;

25 FIG. 5 illustrates an equivalent circuit of a switch in accordance with a second embodiment; and

FIG. 6 illustrates a cross sectional view of a switch in accordance with a third embodiment.

DESCRIPTION OF THE PREFERRED EMBODIMENTS

A description will now be given, with reference to the accompanying drawings, of embodiments of the present invention.

First Embodiment

40 A first embodiment is a case where an isolation level in "OFF" state is less than -30 dB when there is one contact point. Here, the isolation level is low, when the isolation is high.

FIG. 1A illustrates a top view of a switch in accordance with the first embodiment. FIG. 1B illustrates a cross sectional view taken along a line A-A of FIG. 1A. In FIG. 1A, a second electrode 24, a movable beam 40 under an upper electrode 34, a first electrode 22 and a projection electrode 21 are shown with a dotted line. The switch is composed of a substrate 10, the movable beam (a movable portion) 40, a connection portion 20 and a drive portion 30. The substrate 10 has a silicon oxide layer as a sacrificial layer 14 on a silicon substrate 12 and has a silicon layer as a semiconductor layer 16 on the sacrificial layer 14. The movable beam 40 is composed of a layer that is same as the semiconductor layer 16.

45 One end of the movable beam 40 is fixed to the substrate 10 at a fixing portion 42 through the sacrificial layer 14. A groove 54 is formed around the movable beam 40. The groove 54 reaches to the silicon substrate 12. The sacrificial layer 14 under the movable beam 40 except for the fixing portion 42 is eliminated and a space 52 is formed. The first electrode 22 is provided on the other end of the movable beam 40. The second electrode 24 is provided above the first electrode 22 so as to face an upper face of the first electrode 22. The second electrode 24 is fixed to the substrate 10 at a fixing portion 28.

50 The second electrode 24 has the projection electrode 21. The projection electrode 21 is able to contact with the first electrode 22. This results in that the first electrode 22 and the

second electrode 24 compose the connection portion 20. The drive portion 30 has a lower electrode 32 that is provided on the movable beam 40, and has the upper electrode 34 that is provided above the lower electrode 32 and is fixed to the substrate 10.

FIG. 2A and FIG. 2B illustrate a schematic view showing an operation of the switch in accordance with the first embodiment. As shown in FIG. 2A, the first electrode 22 and the projection electrode 21 of the second electrode 24 are not in touch with each other and a state of the switch is “OFF”, when there is no voltage applied between the lower electrode 32 and the upper electrode 34. As shown in FIG. 2B, an attracting force is generated when a voltage V is applied between the lower electrode 32 and the upper electrode 34 of the drive portion 30. This causes the movable beam 40 provided on the lower electrode 32 to move toward the upper electrode 34 fixed to the substrate 10. This results in that the first electrode 22 is electrically connected to the projection electrode 21 and the state of the switch is changed to “ON” (electrically conducted). When the voltage V is shut off, the state of the switch is changed to “OFF” as shown in FIG. 2A. Accordingly, the device acts as a switch.

A description will be given of a structure that may reduce the isolation level in “OFF” state, with reference to FIG. 3. As shown in FIG. 3, an RF voltage is represented as “ V_o ”, each of power supply side transmission impedance and output load side transmission impedance is represented as “ R_o ”, a current passing through a MEMS switch SW is represented as “ I ”, and a capacitance of the MEMS switch SW is represented as “ C ”. When an electrical power fed into the MEMS switch SW is represented as P_{in} , an electrical power from the MEMS switch is represented as P_{out} , a voltage at an inputting end of the MEMS switch is represented as V_{in} , and a voltage at an outputting end of the MEMS switch is represented as V_{out} at frequency f , these are shown as following expressions.

$$V_{in} = R_o \cdot I + V_o \quad (Expression 1)$$

$$V_{out} = R_o \cdot I \quad (Expression 2)$$

$$\text{Impedance } Z \text{ of the MEMS switch } SW = 1/(j \cdot 2\pi f C) \quad (Expression 3)$$

$(V_{in} - V_{out})$ is shown as following Expression 4 according to Expression 1 through Expression 3.

$$V_{in} - V_{out} = V_o = I/(j \cdot 2\pi f C) \quad (Expression 4)$$

P_{in} and P_{out} are shown as following Expression 5 and Expression 6 respectively according to Expression 1 and Expression 2.

$$P_{in} = |I \cdot V_{in}| = |R_o \cdot I^2 + I \cdot V_o| \quad (Expression 5)$$

$$P_{out} = |I \cdot V_{out}| = |R_o \cdot I^2| \quad (Expression 6)$$

The isolation level IL between the inputting end and the outputting end of the MEMS switch is shown as following Expression 7 according to Expression 5 and Expression 6.

$$IL(\text{dB}) = 10 \log_{10}(|P_{out}/P_{in}|) = 10 \log_{10}(|1 + V_o/(R_o \cdot I)|) \quad (Expression 7)$$

When an operation frequency of the MEMS switch SW is a few GHz and the capacitance C is a few fF, following Expression 8 is obtained.

$$|V_o/(R_o \cdot I)| \gg 1 \quad (Expression 8)$$

Therefore, Expression 6 is shown as following Expression 9 according to Expression 4 and Expression 8.

$$IL(\text{dB}) = 10 \log_{10}(|(R_o \cdot I)/V_o|) = 10 \log_{10}(2\pi f R_o C) \quad (Expression 9)$$

In order to reduce the isolation level less than -30 dB, a relationship shown in following Expression 10 and Expression 11 are necessary.

$$2\pi f R_o \cdot C \leq 10^{-3} \quad (Expression 10)$$

$$f R_o \cdot C \leq 1.6 \times 10^{-4} \quad (Expression 11)$$

When the power supply side transmission impedance R_o and the output load side transmission impedance R_o are 50Ω being commonly used or more than 50Ω, following Expression 12 is obtained.

$$f C \leq 3.2 \times 10^{-6} \text{ F} \cdot \text{s}^{-1} \quad (Expression 12)$$

When the operation frequency is higher than 5 GHz, following Expression 13 is obtained.

$$C \leq 6.4 \times 10^{-16} \text{ F} \cdot 64 \text{ fF} \quad (Expression 13)$$

This results in that the isolation level is less than -30 dB when Expression 11, Expression 12 or Expression 13 is satisfied.

As shown in FIG. 2A, a distance between the projection electrode 21 and the first electrode 22 is represented as “ g ”, an end area of the projection electrode 21 is represented as “ S_g ”, a distance between the first electrode 22 and an area of the second electrode 24 except for the projection electrode 21 is represented as “ h ”, an area of a region where the first electrode 22 and the second electrode 24 are facing to each other is represented as “ S_h ” (a hatched area of FIG. 1A). In this case, “ C ” is shown as following Expression 14.

$$C = \epsilon_0 \cdot (S_h - S_g)/h + \epsilon_0 \cdot S_g/g \quad (Expression 14)$$

Here, when following Expression 15 is satisfied, “ C ” is shown as following Expression 16 approximately.

$$\epsilon_0 \cdot S_h/h \geq (1/10) \times (\epsilon_0 \cdot S_g/g) \quad (Expression 15)$$

$$C \approx \epsilon_0 \cdot S_h/h \quad (Expression 16)$$

Generally, “ g ” is approximately 0.2 μm and “ S_g ” is approximately 1 μm². As mentioned later, “ h ” is a few μm and “ S_h ” is 360 μm². This results in that Expression 15 is satisfied. Therefore, in order to satisfy Expression 13, a relationship shown in following Expression 17 and Expression 18 are necessary.

$$S_h/h \leq 72 \mu\text{m} \quad (Expression 17)$$

$$S_h \leq 360 \mu\text{m}^2 \quad (Expression 18)$$

(in a case where “ h ” is more than 3 μm)

That is, it is preferable that “ S_h ” is less than approximately 19 μm × 19 μm. It is therefore possible to reduce the isolation level IL less than -30 dB when Expression 17 or Expression 18 is satisfied.

Second Embodiment

A second embodiment is a case where states of two connection portions are changed to “ON” and to “OFF” substantially at one time. FIG. 4A illustrates a top view around a connection portion of a switch in accordance with the second embodiment. FIG. 4B illustrates a cross sectional view taken along lines A-A and B-B of FIG. 4A. FIG. 4C illustrates a cross sectional view taken along a line C-C of FIG. 4A. The switch has a second electrode 24a and a third electrode 24b that are able to contact with the first electrode 22 and are fixed to the substrate 10. A high-frequency signal is transmitted from one of the second electrode 24a and the third electrode 24b to the other through the first electrode 22, when the second electrode 24a and the third electrode 24b are in touch

with the first electrode 22 substantially at one time. A projection electrode 21a is provided on the second electrode 24a. A projection electrode 21b is provided on the third electrode 24b. The projection electrodes 21a and 21b are used for coupling the second electrode 24a and the third electrode 24b to the first electrode 22 respectively. Other structures are in common with the first embodiment. With the structure, it is possible to turn on and turn off the flow of electrical power from the second electrode 24a to the third electrode 24b.

FIG. 5 illustrates an equivalent circuit of a switch in "OFF" state in accordance with the second embodiment. Two capacitances C1 are coupled to the MEMS switch SW in series, being different from FIG. 3. When the capacitances at the two connection portions 20 are substantially equal to each other, a relationship shown in following Expression 19 is necessary according to Expression 11, in order to reduce the isolation level less than -30 dB.

$$fR_o \cdot C1 \leq 3.2 \times 10^{-4} \quad (\text{Expression 19})$$

When the power supply side transmission impedance R_o and the output load side transmission impedance R_o are more than 50Ω , following expression 20 is obtained.

$$fC1 \leq 6.4 \times 10^{-5} \text{ F} \cdot \text{s}^{-1} \quad (\text{Expression 20})$$

When the operation frequency is higher than 5 GHz, following Expression 21 is obtained.

$$C1 \leq 12.8 \times 10^{-16} \text{ F} = 128 \text{ fF} \quad (\text{Expression 21})$$

This results in that the isolation level is less than -30 dB when Expression 19, Expression 20 or Expression 21 is satisfied.

As shown in FIG. 4A and FIG. 4B, a distance between the first electrode 22 and a region of the second electrode 24a and the third electrode 24b except for the projection electrode 21 is represented as "h". An area of a region where the first electrode 22 faces the second electrode 24a and the third electrode 24b is represented as " S_h ". In this case, "C1" is shown in following Expression 22 similarly to Expression 15.

$$C1 = \epsilon_0 \cdot (S_h - S_g) / h + \epsilon_0 \cdot S_g / g \quad (\text{Expression 22})$$

When following Expression 23 is satisfied, following Expression 24 and Expression 25 are obtained.

$$\epsilon_0 \cdot S_h / h \geq (1/10) \times (\epsilon_0 \cdot S_g / g) \quad (\text{Expression 23})$$

$$S_h / h \leq 144 \mu\text{m} \quad (\text{Expression 24})$$

$$S_h \leq 720 \mu\text{m}^2 \quad (\text{Expression 25})$$

(in a case where "h" is more than 3 μm)

That is, it is preferable that " S_h " is less than approximately 27 $\mu\text{m} \times 27 \mu\text{m}$.

This results in that the isolation level is less than -30 dB in the second embodiment when Expression 24 or Expression 25 is satisfied. It is preferable that Expression 19, 20, 21, 24 or 25 is satisfied with respect to both of the connection portions 20.

When one of the connection portions 20 is electrically shorted or the capacitance of one of the connection portions 20 is very large, the isolation level is maintained with the other connection portion 20. In this case, the isolation level is less than -30 dB when Expression 11, 12, 13, 17 or 18 in the first embodiment is satisfied.

Third Embodiment

A third embodiment is a case where the projection electrode 21 is provided on the first electrode 22. FIG. 6 corresponds to FIG. 4B. The projection electrode 21 may be pro-

vided on the first electrode 22. And, the projection electrode 21 of one of the two connection portions 20 may be provided on the first electrode 22. The projection electrode 21 of the other connection portions 20 may be provided on the second electrode 24a or on the third electrode 24b.

It is preferable that the first electrode 22 has the projection electrode 21 for contacting with the second electrode 24a and the third electrode 24b or that the second electrode 24a and the third electrode 24b have the projection electrode 21 for contacting with the first electrode 22, as shown in the second embodiment and the third embodiment. And, the projection electrode 21 may be provided on the first electrode 22 in the first embodiment.

In the first through the third embodiments, the projection electrode 21 is provided. However, the projection electrode 21 may not be provided if the first electrode 22 can be electrically connected and unconnected to the second electrode 24 or if the first electrode 22 can be electrically connected and unconnected to the second electrode 24a and the third electrode 24b. Further, a plurality of the projection electrodes 21 may be provided on one connection portion 20.

In the above-mentioned embodiments, the drive portion 30 is an electrostatically driving portion that moves the movable beam 40 when a voltage is applied between the lower electrode 32 and the upper electrode 34. The drive portion 30 may move the movable beam 40 (a movable portion), and may be a piezo drive portion, a heat drive portion, or a magnetic drive portion. And, in the above-mentioned embodiments, the switch is a normally off type switch of which state is "OFF" when no voltage is applied to the drive portion 30. The switch may be a normally on type switch. In the above-mentioned embodiments, one end of the movable beam 40 is fixed to the substrate 10 and the other end has the connection portion 20. The movable portion may act as a connection point at the connection portion 20 when the movable portion moves with respect to the substrate 10.

While the preferred embodiments of the present invention have been illustrated in detail, the invention is not limited to the specific embodiments above. In addition, it will be appreciated that the invention is susceptible of modification, variation and change without departing from the proper and fair meaning of the accompanying claims.

The present invention is based on Japanese Patent Application No. 2006-204136 filed on Jul. 27, 2006, the entire disclosure of which is hereby incorporated by reference.

What is claimed is:

1. A switch comprising:
a movable portion that is provided on a substrate and moves with respect to the substrate;

a first electrode that is provided on the movable portion;
and

a second electrode that is able to contact with the first electrode and is fixed to the substrate,

wherein:

one of the first electrode and the second electrode is connected to a power supply;

the other of the first electrode and the second electrode is connected to an output load; and

$f \times R_o \times C \leq 1.6 \times 10^{-4}$ when an operation frequency is represented as "f" (Hz), a transmission impedance of each of the power supply side and the output load side is represented as " R_o " (Ω), and a capacitance in "OFF" state between the first electrode and the second electrode is represented as "C" (F).

2. The switch as claimed in claim 1 further comprising a projection electrode that is provided on one of the first elec-

trode and the second electrode and is able to contact with the other of the first electrode and the second electrode.

3. The switch as claimed in claim 1, wherein $f \times C \leq 3.2 \times 10^{-6}$ F·Hz.

4. The switch as claimed in claim 1, wherein $C \leq 6.4 \times 10^{-16}$ F.

5. The switch as claimed in claim 1, wherein $Sh/h \leq 72 \mu\text{m}$ when an area of a region where the first electrode and the

second electrode face to each other is represented as "Sh" and a distance between the first electrode and the second electrode is represented as "h".

6. The switch as claimed in claim 5, wherein $Sh \leq 360 \mu\text{m}^2$.
